Primary Examiner — Cynthia M. Chin

(57) **CLAIM**

The ornamental design for a scooter, as shown and described.

DESCRIPTION

FIG. 1 is a first perspective view of a scooter showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an enlarged partial view of the front wheel area taken from the right of FIG. 2; and,

FIG. 10 is an enlarged partial view of the rear wheel area taken from the left of FIG. 2.

The dash-dot broken lines represent the boundaries of the enlarged partial views of FIGS. 9 & 10 and form no part of the claimed design.

1 Claim, 10 Drawing Sheets
